UNITED STATES PATENT OFFICE.

HENRI PIEPER, OF LIEGE, BELGIUM.

AIR-PRESSURE BRAKE.

Application filed September 27, 1919. Serial No. 326,825.

To all whom it may concern:

Be it known that I, HENRI PIEPER, engineer, a subject of the King of Belgium, and resident of Liege, in the Kingdom of Belgium, have invented certain new and useful Improvements in Air-Pressure Brakes; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

15 This invention relates especially to the air pressure brakes such as the brake which forms the subject of U. S. Patent No. 1,376,573.

The brake described in said application 20 comprises essentially a cylinder with a brake piston on which an air pressure acts directly, or with interposition of an intermediate liquid, and a solenoid device acting so as to move the piston in opposition to the 25 air pressure. In such a brake system this invention relates to the case where an intermediate liquid is utilized.

One of the objects of this invention is the provision of means whereby the brake may 30 be operated as usual in order to produce the full braking action or the releasing action, or may be operated gradually in order to permit of retaining the brake in any desired intermediate position, so as to obtain 35 a desired regulation in the braking action.

For this purpose, according to the present invention, the valve controlling the passage of the pressure liquid may be opened as usual for permitting a relatively rapid 40 flowing of the liquid or may be removed only a short distance from its seat for producing a reduced flow of the liquid.

Obviously when the liquid flows slowly the shoe of the brake moves slowly and it 45 is possible, by stopping the passage of the liquid at a given moment to check the said shoe in any desired position so as to obtain a moderate braking action.

The invention embodies also means for 50 electrically operating the valve controlling the flow of the liquid.

It is to be further noted that simultaneously with the regulation of the flow of the liquid, means may be utilized for varying 55 the air pressure upon the intermediate

liquid. For this a simple valve controlling the flow of air may be interposed between the tank containing the intermediate liquid and the air pressure reservoir.

The appended drawings show by way of example several preferred embodiments of the invention.

In these drawings:—

Fig. 1 shows diagrammatically an embodiment of the invention, in which the air and liquid are placed in different reservoirs.

Fig. 2 shows another embodiment in which the air reservoir and the liquid reservoir are combined in one and the same reservoir provided with a single valve which always travels the same distance.

Fig. 3 shows an electrical controlling device for the valve.

Fig. 4 shows a diagram of the arrangement for the use of an electrically controlled valve according to Fig. 3 in combination with the usual rheostatic braking by the motor.

Fig. 5 shows a similar arrangement in which the relay of Fig. 4 is omitted.

In the arrangement according to Fig. 1, the brake piston 2 rigidly connected to core 5 of the solenoid 13 moves within the cylinder 1.

The core 5 acts by means of its rod 6 on the mechanical braking arrangement not shown. In a pipe 74 connecting the air reservoir 8 to the brake cylinder 1 is arranged an auxiliary reservoir 65 adapted to be filled with oil in its lower portion and containing a device with two valves 80, 81, the valve 80 controlling the passage of the oil or other intermediate liquid towards the pipe 74 and the cylinder 1 while valve 81 controls the inlet of the pressure air from reservoir 8.

Two electromagnets 82, 83 are used in combination with a spring 84 to move the valves 80 and 81 different distances from their seats. The electromagnets 82, 83 act on a common armature 85 of the valve rod and are in connection with the controller 20 in such manner that by cutting out the current in magnet 82 the valves 80 and 81 rise a limited distance from their seats, under the action of spring 84, whereby slow braking action is produced. The air passes in through valve 81 and the oil which is forced by the air pressure through valve 80 acts upon the piston 2. If on the con- 110

trary the current is cut out in magnet 82 and sent in magnet 83, the valves 80 and 81 rise the maximum distance from their seats permitting air and oil to pass at high speed 5 through the valves and thereby produce rapid braking.

During the releasing operation of the brake, when the circuits of the magnet 82 and of the solenoid 13 are closed, the piston 10 2 presses oil through valve 80 into the intermediate reservoir 65.

As soon as the circuit of solenoid 13 has been cut off by a suitable operation of controller 20, the valve 80 closes and a new 15 braking operation can no more take place although the piston 2 has only effected a portion of its releasing travel to press the air again into the reservoir 8 and the pressure attained has not reached the normal 20 value. Hence it is possible to moderate the releasing action, in other words to reduce more or less the braking action without using the solenoid 13 to move the piston in opposition to the air pressure. That means 25 a considerable reduction in the current consumption and an important simplification of the controller. Without intermediate liquid, it is impossible to obtain such a regulation in the release which does not 30 require the opposite action of the solenoid 13, because it is only at the end of its stroke that the braking piston 2 produces a pressure sufficient to press the air back into the reservoir 8, so that if the current in the 35 solenoid is interrupted before the end of the stroke, the brake is again applied with its full pressure.

In the arrangement according to Fig. 1 the pressure exerted during the braking action 40 may be regulated by opening the valve 81 for different periods of time. The operation of the brake can accordingly be graduated as well in the braking as in the releasing stroke owing to the presence of the intermediate liquid and of the valve device.

Fig. 2 shows another embodiment in which the air reservoir and the liquid reservoir are combined in one and the same reservoir 86; moreover there is only one 50 valve, which travels always the same distance. The reservoir 86 is filled with air in the upper portion 87 and is adapted to be filled with oil in the lower portion 88. The valve 89 which controls the passage of the 55 oil towards the pipe 74 and the cylinder 1 is operated by means of an electromagnet 90 which, when unexcited, permits the valve to open under the action of the spring 91. The other features of the device are the 60 same as in Fig. 1. When braking is required, the current is cut off in the magnet 90, which results in the opening of valve 89, and the oil is allowed to act on piston 2 under the influence of the air pressure. By 65 releasing the valve 89 closes as

soon as the piston 2 stops in consequence of the cutting off of the current in solenoid 13, for instance half way in its travel, the liquid acting then on the valve to close it. It is thus possible in the case of Fig. 2 to 70 apply the brake blocks with more or less pressure without using the opposing action of the solenoid. In this arrangement the pressure of the air on the oil cannot be regulated, but the elasticity in the whole arrangement, and more particularly in the rods and levers transmitting the power to the braking blocks, is sufficient to graduate the braking action in a practically acceptable manner.

It is also possible to include in the arrangement according to Figs. 1 and 2 suitable devices with two valves with different opening sections, similar to that described in Patent No. 1,376,573.

The arrangements which have been described and which comprise one valve or two valves with two different travels, require two electromagnets, one of which acts as to control the valve or the valves to effect 90 the short travel and the other of which produces the full travel of the valve or valves. It is possible to produce these different displacements of the valves by means of a single electromagnet, whereby the arrangement becomes more simple. Fig. 3 shows such a device in combination with a valve having two different displacements.

The valve casing 75 is provided with two ducts. Duct 76 communicates with the oil 100 reservoir on which acts the pressure air and duct 74 communicates with the brake cylinder.

The valve 77 rests on its seat and is thus interposed between the oil reservoir and the brake cylinder. 78 indicates a solenoid wound on a brass pipe 79 containing three iron cores. Core 69 is fixed while cores 92 and 93 are movable.

The core 92 is flat at one end while the 110 other end is bored in the shape of a cone, in which the conical end of the core 93 fits with a little gap. The core 92 is provided with a brass rod 94 which traverses freely the core 93. This rod is provided with a 115 groove 95 in which fits, with a certain play, a pin 15 carried by the core 93. Said core 93 is acted upon by a spring 96 which tends to lift the core 93 and thereby to raise the valve 77.

Assume the solenoid 78 is excited. The magnetic flux traverses successively the gap 97 and the gap 14 and closes through the iron breech around the solenoid 78. When the magnetic flux is sufficient to cause the core 69 to attract the core 92 and the latter to attract the core 93, the spring 96 is thereby compressed.

As the surface of the conical gap 14 is larger than the surface of the flat gap 97, the

same flux traversing the system, a greater part of flux will pass through the unit of surface in the flat gap 97 than in the conical gap 14 thus producing a greater attraction 5 between the cores 92 and 69 than between the cores 92 and 93; this difference in the attractions is increased by the fact that the attractive power in the conical gap 14 is directed obliquely with respect to the axis.

- 10 There is made use of this property in order to obtain two different displacements of the valve 77. If a suitable resistance is inserted in the circuit of the solenoid 78, the magnetic flux is decreased and becomes insufficient to 15 maintain cores 92 and 93 in contact with each other, but is yet sufficient to maintain the core 92 in contact with the core 69, notwithstanding the action of the spring 96 tending to keep the said cores away from each other. 20 Hence the core 93 is lifted a distance equal to the play between the pin 15 and the bottom of the groove 95 in rod 94; as a result the valve 77 is raised a little.

If the current is then completely stopped 25 in the solenoid 78, the core 93, under the action of the spring 96, lifts the core 92 and consequently the valve 77 is raised completely.

When the normal current is re-established 30 in the solenoid 78 the core 69 attracts the core 92 and the latter attracts the core 93 which compresses the spring 96 and the valve 77 falls back on its seat.

It is apparent that this arrangement here- 35 tofore described permits, by means of a single solenoid two definite displacements of the valve to be obtained; the short travel takes place when the current is suitably reduced in the solenoid and the full one when the current is completely interrupted.

The core 69 is screwed in the pole piece of 40 the solenoid 78. By screwing it more or less it is possible to vary the play between the pin 15 of core 92 and the groove 95 in rod 94, whereby it is possible to regulate the short travel of the valve. As this travel corresponds to the slow action of the brake, it is thus possible to regulate very easily the 45 rapidity of action by braking. The arrangement according to Fig. 3 is very simple and very sure in operation.

The intermediate liquid and the corresponding valve may also be arranged between the solenoid and the brake piston in 50 such a manner that said liquid is in communication with the portion of the brake cylinder adjoining the solenoid, while another liquid may in this case be placed between the air and the piston, without insertion of a valve. Besides it is possible to control all the brakes of a train from a single 55 controlling stand in the manner described in the patent hereinbefore mentioned. In all these arrangements the brake works automatically in the cases of interruption of the 60

current in the line or of breaking of the couplings.

In tramway constructions there is often made use of the rheostatic braking by the motors, as an auxiliary brake. The air brake 70 according to the present invention permits the action of the rheostatic braking, by the use of the arrangement shown in Fig. 4. In the circuit of the rheostatic braking 16, 17 is inserted a little electro-pneumatic relay 18 75 which when unexcited closes the circuit of the solenoid 78 which controls the valve or valves. But in a case of danger when the motorman must obtain a rapid braking, he has but to manipulate the handle crank of 80 the controller 22 for the motors 19 in such a manner as to cause these motors to work as generators and to feed current through the resistance 23 and the relay 18. When the latter is excited its armature 21 is attracted 85 and the circuit of the coil 78 of the valve 77 is interrupted, which results in the automatic working of the electro-pneumatic brake 5, the retarding action of which is to be added to that of the motors.

The same result can be realized without the use of a relay by the arrangement according to Fig. 5. The coil 78 which controls the valve or valves 77 is provided with a second winding 78^A inserted in the circuit of the 90 rheostatic braking 16, 17 and in which the current fed by the motors 19 when working as generators, will pass in an opposite direction to that in the first winding 78, so as to produce a demagnetizing effect.

It is apparent that when the motor-man makes use of the rheostatic braking the current which passes in the second winding 78^A causes the valve or valves 77 to rise and the electro-pneumatic brake 5 is automatically 100 put into action.

Hence by rotating the handle crank of the main controller, braking by the motors and braking by the brake blocks take place simultaneously. This important result is attained in a very simple and very economic manner.

What I claim is:

1. In an electro-pneumatic brake comprising a cylinder with a brake piston, an air pressure reservoir; a reservoir containing a liquid on which the air pressure acts; a pipe for admitting the liquid pressure to the brake cylinder; a valve device controlling the flow of the liquid through said pipe; a solenoid having a core which is rigidly connected to the piston and acts so as to move the piston in opposition to the air pressure; means for controlling the air pressure acting on the liquid; and means 115 permitting of the brake to be slowly released in such a manner that the releasing may be interrupted in any desired place so as to permit of a regulation of the releasing.

2. In an electro-pneumatic brake comprising a cylinder with a brake piston, an air pressure reservoir; a reservoir containing a liquid on which the air pressure acts; a pipe for admitting the liquid pressure to the brake cylinder; a valve device controlling the flow of the liquid through said pipe; a solenoid having a core which is rigidly connected to the piston and acts so as to move the piston in opposition to the air pressure; an electrically operated valve controlling the flow of the air coming from and going to the air pressure reservoir; and means permitting the brake to be slowly released in such a manner that the releasing may be interrupted in any desired place so as to permit of a regulation of the releasing.

3. In an electro-pneumatic brake comprising a cylinder with a brake piston, an air pressure reservoir; a reservoir containing a liquid on which the air pressure acts; a pipe for admitting the liquid pressure to the brake cylinder; a valve controlling the flowing of the liquid through said pipe; an electrically operated stem for opening and closing said valve; means for attaching said valve to said stem to permit a relative displacement between the valve and the stem when the liquid pressure acts from the brake piston towards the air pressure reservoir thereby producing a slight passage for the flow of the liquid and consequently a slow releasing of the brake; means for electrically displacing the stem in order to close the valve in any position during the slow releasing of the brake to permit a regulation of the braking action; a solenoid having a core which is rigidly connected to the piston and acting to move the piston in opposition to the air pressure; and means for controlling the air pressure acting on the liquid.

4. In an electro-pneumatic brake comprising a cylinder with a brake piston, an air pressure reservoir; a reservoir containing a liquid on which the air pressure acts; a pipe for admitting the liquid pressure to the brake cylinder; a valve controlling the flow of the liquid through said pipe; an electrically operated stem for opening and closing said valve; means for attaching said valve to said stem to permit a relative displacement between the valve and the stem when the liquid pressure acts from the brake piston towards the air pressure reservoir thereby producing a slight passage for the flow of the liquid and consequently a slow releasing of the brake; means for electrically displacing the stem in order to close the valve in any position during the slow releasing of the brake to permit a regulation of the braking action; a solenoid having a core which is rigidly connected to the piston and acts to move the piston in opposition to the air pressure; and an elec-

trically operated valve controlling the flow of the air coming from and going to the air pressure reservoir.

5. In an electro-pneumatic brake comprising a cylinder with a brake piston, an air pressure reservoir; a reservoir containing a liquid on which the air pressure acts; a pipe for admitting the liquid pressure to the brake cylinder; a valve controlling the flow of the liquid through said pipe; an electrically operated stem for opening and closing said valve; means for electrically displacing said stem during the releasing of the brake to permit the valve to be slightly displaced relatively to its seat thus opening a little passage for the flowing of the liquid and producing a slow releasing of the brake; and a solenoid having a core which is rigidly connected to the piston and acts to move the piston in opposition to the air pressure.

6. In an electro-pneumatic brake comprising a cylinder with a brake piston, an air pressure reservoir; a reservoir containing a liquid on which the air pressure acts; a pipe for admitting the liquid pressure to the brake cylinder; a valve controlling the flow of the liquid through said pipe; a stem actuating said valve; a solenoid having a core carrying said stem, said solenoid having a second core; an abutment limiting the distance between the said cores; said solenoid having a third core firmly attached thereto; a spring acting to keep the said cores away from each other, the surfaces of air gaps of the first and second cores being inclined differently from the surfaces of air gaps of the second and third cores; means for varying the magnetic intensity developed in the said solenoid; and a second solenoid having a core which is rigidly connected to the piston and acts to move the piston in opposition to the air pressure.

7. In an electro-pneumatic brake comprising a cylinder with a brake piston, an air pressure reservoir; a reservoir containing a liquid on which the air pressure acts; a pipe for admitting the liquid pressure to the brake cylinder; a valve controlling the flow of the liquid through said pipe; a stem actuating said valve; a solenoid having a core carrying said stem, said solenoid having a second core; an abutment limiting the distance between the said cores; said solenoid having a third core firmly attached to the solenoid; a spring acting to keep the said cores away from each other, the surfaces of air gaps of the first and second cores being inclined differently from the surface of air gaps of the second and third cores; means for feeding current in said solenoid through a relay inserted in a rheostatic braking circuit of the motors; means for regulating said current; and a second solenoid having a core which is rigidly con-

nected to the piston and acts to move the piston in opposition to the air pressure.

8. In an electro-pneumatic brake comprising a cylinder with a brake piston, an air pressure reservoir; a reservoir containing a liquid on which the air pressure acts; a pipe for admitting the liquid pressure to the brake cylinder; a valve controlling the flow of the liquid through said pipe; a stem actuating said valve; a solenoid having a core carrying said stem, said solenoid having a second core; an abutment limiting the distance between the said cores; said solenoid having a third core firmly attached to the solenoid; a spring acting to keep the said cores away from each other; the sur-

faces of air gaps of the first and second cores being inclined differently from the surfaces of air gaps of the second and third cores; a demagnetizing coil disposed around the magnetizing coil of the said solenoid and inserted in a rheostatic braking circuit of the motors; and a second solenoid having a core which is rigidly connected to the piston and acting so as to move the piston in opposition to the air pressure.

In testimony whereof I affix my signature in presence of two witnesses.
